(74) Attorney, Agent, or Firm—Krieg DeVault LLP

(57) **CLAIM**

The ornamental design for headphone ear tips, as shown and described.

DESCRIPTION

FIG. 1 is a perspective view of headphone ear tips showing my new design;

FIG. 2 is a top view thereof;

FIG. 3 is a front elevational view thereof;

FIG. 4 is a right side elevational view thereof;

FIG. 5 is a left side elevational view thereof;

FIG. 6 is a back elevational view thereof;

FIG. 7 is a bottom view thereof; and,

FIG. 8 is a bottom perspective view thereof.
